VELOCIPED FENDER

Harry Golden, New York, N.Y., assignor to Ideas for
Auto and Bike Specialties, Inc., New York, N.Y., a
corporation of New York

Filed Nov. 4, 1968, Ser. No. 14,300

Term of patent 14 years

Int. Cl. D12—14

U.S. Cl. D90—5

FIG. 1

FIG. 2

FIG. 3

FIG. 4

FIG. 1 is a side elevational view of a velocipede fender embodying my new design, with the opposite side being identical in appearance.

FIG. 2 is a top plan view thereof,

FIG. 3 is an end view thereof, looking to the right in FIG. 1; and

FIG. 4 is an end view thereof, looking to the left in FIG. 1.

I claim:

The ornamental design for a velocipede fender, as shown.
